ROTARY DRUM FILTER

Frank W. Young, Upper Montclair, N. J.

Application June 23, 1934, Serial No. 732,057

7 Claims. (Cl. 210—202)

This invention relates to rotary drum filters, and in particular to the construction of the drum and valve of such filters.

Continuous rotary drum filters as at present constructed consist of a drum, the outer surface of which is provided with individual compartments. Each of these compartments communicates with an automatic valve carried on one end of the trunnion by means of suitable piping. By means of this automatic valve each of the compartments may be successively subjected to sub-atmospheric or atmospheric pressure as desired, for the purpose of forming a cake on the surface of the drum and then discharging it.

One of the objections to the filters now on the market is that the restriction to the flow of liquid in the pipes, T's and elbows connecting the filter compartments with the automatic valve materially decreases the capacity of the filter. Furthermore, when the drum is provided with closed heads or ends, the buoyancy of the drum requires extra heavy construction to take care of the stresses and strains set up by these unbalanced conditions.

In general the object of this invention is to provide a continuous rotary drum filter in which the network of piping within the drum is eliminated.

More specifically the object of the invention is the provision of a drum for continuous filters, the outer surface of which is provided with independent compartments, each communicating by means of ports with the interior of the drum, and each port having associated with it a valve in the form of a counterbalanced gravity operated shoe suspended adjacent each of said ports.

A further object of the invention is the provision of a drum having closed ends in which the filtrate within the drum is substantially at the same level as the pulp within the tank in which the drum rotates to thereby eliminate any buoyant effect of the drum.

The invention possesses other advantageous features, some of which with the foregoing, will be set forth in the following description where that form of the invention which has been selected for illustration in the drawing accompanying and forming a part of the present specification is outlined in full. In said drawing, one form of the invention is shown, but it is to be understood that it is not limited to such form, since the invention as set forth in the claims may be embodied in a plurality of forms.

Referring to the drawing:

Figure 1 is a side elevation partly in section of

a rotary drum filter in which the objects of the invention are embodied.

Figure 2 is a section taken on the line 2—2 of Fig. 1.

Figure 3 is an enlarged perspective view of one of the counterbalanced gravity operated valves used within the filter drum.

In accordance with the invention, a drum 1, provided with closed heads 2 and 3, is rotatively disposed within a tank 4 by means of trunnions 5 and 6, journaled in bearings 7 and 8. The trunnion 5 is hollow as clearly shown in Figure 1 and serves to establish communication between the interior of drum 1 and a suitable vacuum pump (not shown) for subjecting the interior of the drum and its contents to sub-atmospheric pressure. The trunnion 6 is closed by means of a plate 9, and has associated with it a gear train 11 which in turn is driven by means of a motor 12 carried by a suitable bracket formed on one end of the tank, and the bearing 8.

The outer surface of the drum 1 is provided with independent filtrate compartments 13, defined by the usual division strips 14. Disposed over the division strips 14 is a supporting screen 15 which in turn is covered by any suitable filter medium 16. A port 17 is formed in the floor of each compartment for the purpose of establishing communication between the interior of each compartment and the interior of the drum 1. Communication between the compartments 13 and the interior of the drum is controlled by means of a counterbalanced gravity operated valve as clearly shown in Figure 3, and which consists of a fitting 18 provided at one end with a flange 19 and at its opposite end with brackets 21 in which are formed bearings 22. Journaled in the bearings 22 is a shaft 23, to the central portion of which is secured an arcuate shoe or gate 24, and to the outer ends of which are secured counterweights 25. The radius of curvature of the arcuate shoe 24 is made complementary to the radius of curvature of the free ends 26 of the fitting 18 so that upon the relative rotation of the shoe 24 and the fitting 18 these members will just clear each other. Under actual operating conditions the entire valve mechanism is wetted by the filtrate contained within the drum 1, and therefore although there is some clearance between the shoe 24 and the fitting 18 the shoe 24 under these conditions effectively closes the free open end or port of the fitting 18. As shown in Figure 2 the fittings 18 are secured to the inner face of the drum 1 in registration with the port 17 by means of the flange 19. If the

40

45

50

55

drum 1 is of relatively small diameter or if the compartments 13 are relatively narrow, it is preferable to stagger the ports 17 as shown in Figure 1.

5. By adjusting the relative angular position of the shoe 24 and the counterweights 25 (which may be done by suitable setscrews carried by the hubs of the counterweights 25) the shoe 24 may be made to close the open ends of their associated fittings 18 during any particular point of the revolution of the drum 1. As shown in Figure 2 the valves in this instance are closed only on the upper side of the drum during the discharge period of the cycle. The filtrant within the tank 4 is carried at a level indicated by the line 27 and since the cake forming period should commence as soon as any given compartment is submerged within the filtrant, the valve associated with this compartment should be open or begin to open at this point, and should remain open during the entire cake forming period and during the cake drying period so that cake formation and drying may be effected under the influence of sub-atmospheric pressure.
25. The counterweights 25 should of course be heavy enough to prevent any appreciable rotation of the shoe 24.

It will be noted that by the construction above disclosed the usual automatic valve carried on the end of the drum trunnion has been eliminated, and likewise all of the piping, elbows and T's which have previously been required to establish communication between the filtrate compartments and the valve. In so doing the restriction to the flow of filtrate through the pipes has also been eliminated, and consequently a filter of very high capacity has been provided. Furthermore since the ends of the drum are closed and since the level of the filtrate within the drum is substantially the same as the level of the filtrant within the tank, the drum has substantially no buoyant effect, and therefore it is not necessary to provide an extra heavy construction.

45. I claim:

1. A drum for continuous filters provided on its outer surface with independent filtrate compartments; each filtrate compartment being provided with a port communicating with the interior of the drum and with a gravity operated valve pivoted about an axis parallel with the axis of the drum and adapted to successively open and close said ports upon the rotation of the drum.

2. A drum for continuous filters provided on its outer surface with independent filtrate compartments each compartment having a port communicating with the interior of the drum and a

counterbalanced gravity operated shoe pivoted adjacent said drum about an axis parallel with the axis of the drum, and in line with said ports so that each port is closed by its associated shoe once during each rotation of the drum.

3. A drum for continuous filters provided on its outer surface with independent filtrate compartments, each compartment having a port formed in its floor communicating with the interior of said drum, the centers of said ports lying in a common plane; and a gravity operated shoe pivoted adjacent said ports about an axis parallel with the axis of the drum, and with its center lying in said common plane so that said ports are closed once during each rotation of the drum.

4. A drum for continuous filters provided on its outer surface with independent filtrate compartments, each compartment being provided with a port communicating with the interior of the drum; a gravity operated counterbalanced shoe pivoted adjacent each of said ports about an axis parallel within the axis of the drum and adapted to close its associated port upon relative motion therewith.

5. A filter comprising a closed ended drum provided with independent filtrate compartments and rotatably mounted within a tank; a port in each compartment communicating with the interior of the drum; sleeve fittings secured to the interior of said drum adjacent said ports and counter balanced shoes journaled in said fittings and arranged to open and close the ends thereof once during each revolution of said drum.

6. In a rotary drum filter provided with independent filtrate compartments each having a port communicating with the interior of the drum; sleeves secured over said ports; shoes rotatably secured to said sleeves and arranged in one position to register with and close the outer ends thereof; and counter weights associated with said shoes for maintaining them in a predetermined position.

7. In a rotary drum filter provided with independent filtrate compartments each having a port communicating with the interior of the drum; sleeves secured over said ports; pins journaled to said sleeves; shoes secured to said pins and adapted in one position to register with and close the outer ends of said sleeves; and counter weights adjustably secured to said pins so that said shoes may be held in any predetermined position and thereby made to register with said sleeves during a predetermined point in the cycle of rotation of said drum.
